CLAIM

I claim the ornamental design for a gaming machine and display, as shown and described.

DESCRIPTION

FIG. 1 is a perspective view of the gaming machine and display in accordance with the first embodiment;

FIG. 2 is a left-side view of the gaming machine and display thereof;

FIG. 3 is a right-side view of the gaming machine and display thereof;

FIG. 4 is a top view of the gaming machine and display thereof;

FIG. 5 is a perspective view of the gaming machine and display in accordance with the second embodiment;

FIG. 6 is a left-side view of the gaming machine and display thereof;

FIG. 7 is a right-side view of the gaming machine and display thereof; and,

FIG. 8 is a top view of the gaming machine and display thereof.

The broken line showing of portions of the gaming machine and display depicts environment and forms no part of the claim.

1 Claim, 8 Drawing Sheets
